UNITED STATES PATENT OFFICE.

OLOF SÖDERLUND, TEOFON BOBERG, AND NILS TESTRUP, OF LONDON, ENGLAND,
ASSIGNORS TO TECHNO-CHEMICAL LABORATORIES, LIMITED, OF LONDON, ENGLAND.

SEPARATING SOLIDS FROM LIQUIDS.

Application filed August 30, 1923. Serial No. 660,234.

To all whom it may concern:
Be it known that we, OLOF SÖDERLUND and TEOFON BOBERG, both subjects of the King of Sweden, and both residing at "Fairlawn," 5 Clarence Road, Clapham Park, London, S. W. 4, England, and NILS TESTRUP, a British subject, and residing at 47 Victoria Street, London, S. W. 1, England, have invented certain new and useful Improvements in or Relating to Separating Solids from Liquids, of which the following is a specification.

This invention relates to the treatment of moist material of the type in which liquid matter is more or less held or retained by matter of a comparatively solid nature as, for example, in peat, lignite, vegetable matter such as seeds and many other materials from which it is frequently desired to separate or expel some of the liquid content for the purpose of bringing the material to a dry or drier state or separating liquid which is to serve some useful purpose.

The entry or bite of a pair of rolls coacting together to effect a squeezing operation for separating liquid as above is of a configuration generally resembling a wedge with inwardly curved or hollowed sides instead of plain tapering ones. The angle between the sides will, therefore, vary from a maximum at the large end to a minimum or zero at the apex or locality of maximum pressure where the rolls most closely approach one another.

Depending upon the nature of the material being pressed there will be some limiting angle and/or distance between the pressing surfaces beyond which the forces tending to drive the material out of the bite will overcome those tending to draw it in, but the greater the distance of this region from the locality of maximum pressure on the material the greater will be the output from the machine for several reasons.

The object of the present invention is to provide improved methods of and/or apparatus for reducing or separating by a squeezing action the liquid content of materials.

The invention consists in a method of and/or apparatus for obtaining increased output from appliances of the type indicated, according to which carrying or feeding members such as endless bands are ar-

ranged to travel through the bite of the rolls with the material undergoing treatment. The invention further consists in a method and/or apparatus as indicated, in which a localized stream or trail of matter is applied, preferably in the centre, to the moving surface or surfaces and by a rolling or like pressure is spread thereon to a thinner and broader strip of drier consistency from which the separated liquid or wetter portion is expelled more or less transversely in more than one direction.

The invention further consists in a method and/or apparatus as indicated according to which heat treatment or further drying or reduction of the liquid content of the thin strip is effected by supplying heat to the surface or material thereon.

The invention further consists in a method and/or apparatus as indicated, in which the material is pressed between two surfaces which curve in the same direction as when the external surface of a cylinder coacts with the internal surface of a hollow cylinder or encircling member.

The invention also consists in improvements in or relating to the reduction or separation of the liquid content of moist or liquid-bearing materials as hereinafter described.

Referring now to the accompanying drawings:

Figures 1, 2, 3 and 4 are diagrams showing the difference in the entry or bite of various rollers and other pressing and carrying surfaces;

Figure 5 is a perspective view of a multi-band press looking at the entry or feeding side;

Figure 6 is a similar view, but looking from the other side;

Figure 7 is a diagrammatic plan showing the entry or bite of a pair of vertical rolls;

Figure 8 is a fragmentary vertical section showing an embodiment for feeding rolls of the foregoing type;

Figure 9 is a more or less diagrammatic plan view of a press provided with a greater number of bands;

Figure 10 is a fragmentary section of the feeding arrangement therefor.

Figure 1 shows the bite of a pair of rolls

and it will be seen that the more or less wedge-shaped configuration of the space *a* where the material will enter between the rollers when rotating in the direction shown 5 by the arrows is wide in proportion to its length and that the transverse dimensions or the distances between the periphery of the rollers decrease in such a manner that the reduction is very rapid and the inclina- 10 tion of the two surfaces to one another is considerable at the commencement and more gradual as the point of contact or maximum grip is reached. For this reason the material can only be properly gripped between 15 the two surfaces when it is very close to the point of maximum pressure and the amount of material carried through will, therefore, be small because if the space is filled beyond a certain distance a very great 20 proportion will be forced back owing to the outward resultant of the pressure on the material being greater than the frictional resistance to its movement along the pressing surfaces.

25 Figure 2 shows the contact between a pair of rolls of very much greater diameter and here it will be noted that the transverse dimensions are much smaller in proportion to the length and that the variation in the 30 transverse dimensions is of a much more uniform nature, while the inclination of the two surfaces to one another is much less. The material in the space *a* will, therefore, be gripped at a much greater distance from 35 the region of maximum pressure and a larger proportion will be carried through the grip. As, however, the size of a press having rolls of these proportions would be very great practical considerations would 40 prevent such an arrangement being adopted with any degree of commercial success.

45 Figure 3 shows an arrangement which in accordance with the invention provides for a greatly increased output by the arrangement of a carrying or feeding member in the shape of an endless band 3 which travels through the bite of the rolls with the material undergoing treatment.

50 The rolls are of similar size to those shown in Figure 1 and the band 3, of which a short portion only is shown, may encircle one or other of the rolls 1, 2 and the pressure exerted upon it at the locality of maximum pressure is sufficient to ensure that it 55 is driven at the same surface velocity as the rolls, so that it will provide upon each side of it an additional surface in contact with the material which is being fed in and capable of exerting a frictional grip thereon.

60 In addition the intermediate band, by halving the wedge-shaped cavity or bite, reduces both the angles which the contacting surfaces make with one another and also the distances between the surfaces so that 65 with the additional band the material may

be fed to the bite at a considerably greater distance from the locality of maximum pressure without a large proportion being rejected in the manner already indicated. This again gives a much greater length of 70 travelling surface in contact with the material and consequently a longer pressing time in addition to a greater frictional grip on the material, so that under such circumstances the travelling surfaces may be run at 75 a considerably higher speed. All of the above conditions result in a very greatly increased output from a machine which will be substantially the same as in the case of Figure 1 with only the addition of the travelling band between the rollers.

Figure 4 shows a pair of rolls of the same diameter as the rolls in Figure 1 but in this case three separate endless bands are arranged round each of the rolls, so that six 80 bands pass together through the entry or bite. In this arrangement it is possible to provide seven separate entries of gradually decreasing transverse dimensions, each cavity resembling very closely a uniformly 85 tapering wedge which may be slightly bent to a curvature in one direction or the other so that a very large amount of material may be gripped between the moving surfaces and all of it be drawn through the 90 region of maximum pressure and thus subjected to the necessary squeezing action.

As an example of the improvement which may be obtained by the use of gradually 95 and substantially uniformly tapering entry 100 cavities and reduced distances and angles between the surface it has been found that with two drums having each a diameter of 20 inches there was obtained, when squeezing raw peat, an output in the neighborhood of 5 kg. of solids per hour per lineal metre surface, whereas when a ring with a diameter of 24 inches was put round one of these drums and raw peat was squeezed on one side of the ring only with the same 105 pressure between the outer surface of the inner drum and the inner surface of the ring a much larger output, say in the neighborhood of some four times the amount 110 of solids per hour per lineal metre surface, 115 was obtained.

Two rolls in accordance with Figures 3 and 4 and provided with any suitable number of encircling bands may be arranged 120 with the axes vertical, horizontal or in any other suitable direction parallel to one another, the rolls being mounted in a suitable frame with the distance apart adjustable so that room for the thickness of two or any greater number of rings or bands and the material carried thereby is left between them. In this way it is possible to obtain in a single apparatus and by the addition 125 only of the extra bands a squeezing capacity 130 having entry cavities or bites of a far more

satisfactory configuration and capable of an output many times exceeding the actual increase in the number of bites provided.

The hollow cylinders, bands or rings may be rigid or have any desired degree of flexibility so long as they have sufficient resilience to regain their original shape after any deflection which might take place. The number of rings or bands between a pair of rolls may also be increased to any desirable extent, each roll being encircled by two, three or any other practical number of bands.

In the arrangement according to Figures 5, 6, 7 and 8 two rolls b, b' are arranged to rotate about their vertical axes on spindles c, c' mounted in bearings in a frame comprising upper and lower horizontal members d, d' and vertical connecting members d^2, d^3 .

The roller b is surrounded by two flexible endless bands e, e' and the roll b' is surrounded by two similar bands e^2, e^3 , said bands being suitably positioned by guide rollers f and any other supporting means (not shown in the drawing).

The four bands e, e', e^2, e^3 pass together through the bite of the rolls and upon the entry side there is fitted a feed box g to which material such as pulped peat or other matter which is to be freed of part of its liquid content is delivered from a feed hopper g' which may be provided with a taper feed worm or screw operating in a gradually tapering extended portion g^2 .

The feed box g communicates with the entry space formed between upper and lower cover plates g^3 and g^4 and a series of vertical positioning bars g^5 extending from the upper to the lower plate around the outer edge thereof.

The upper plate g^3 is perforated with a more or less sector-shaped aperture through which the peat passes from the feed box into the entry spaces between the bands. The lower plate g^4 covers the whole of the bottoms of the entry spaces and both plates overlap the edges of the two rolls, as shown by dotted lines at g^6 in Figure 7, and terminate shortly before reaching the region of maximum pressure, as shown at g^7 , in order to provide spaces for the extruded wetter or more liquid constituents of the matter being pressed. The positioning bars g^5 also constitute supports for scrapers h carried upon the outer sides thereof and adapted to coat with the surface of the rolls and both sides of the bands. The scrapers remove the drier constituents of the matter from the bands and rolls on to a chute h' , from which it may be carried to any desired locality.

In some instances the material to be pressed passes into the bite as a continuous layer extending the full width of the pressing surfaces of the bands and rollers, but in most instances it is preferable to provide

pillar studs (as shown at i , Figures 7 and 8) which extend across each of the feed compartments from the upper to the lower cover plates and just beyond the inner edge of the feed aperture in the upper plate. These pillar studs are provided with central slots or apertures i' (Figure 8) which localize the feed to a restricted strip occupying the central portion of the pressing surfaces of a band or roller and providing a space on the surfaces upon each side of the feed over which the material may be squeezed in a transverse direction, while the more liquid constituents are passing therefrom to be extruded at the edges of the surfaces.

In the embodiment of the invention illustrated by way of example in Figures 5 and 8 power is supplied to a pulley j upon a horizontal shaft j' communicating by bevel gearing j^2, j^3 with a vertical shaft j^4 carrying at its lower end a pinion j^5 gearing with a toothed wheel j^6 on the spindle of one of the rolls and gearing with another similar toothed wheel j^7 on the spindle of the other roll.

Wipers k, k' and other suitable contrivances, blowing or suction devices or the like may be provided for removing the extruded more liquid constituents from the edges of the bands and rollers and conducting this portion of the matter treated by means of suitable conduits (not shown in the drawing) to a tank or other location from which it may be disposed of as desired.

Figures 9 and 10 show in a more or less diagrammatic manner another embodiment of the invention, in which each of the rolls b, b' is surrounded by ten travelling bands, the bands being supported and positioned by edge runners l and guide rollers f and provided with scrapers h for the dried material.

The rolls b, b' are again arranged with their axes vertical and rotated on spindles carried in bearings m, m' supported in a suitable girder framing and provided with hydraulic cylinders m for applying the desired pressure over the contact areas of the pressing surfaces. The feeding and driving arrangements in this embodiment are upon similar lines to those already described in connection with the embodiment shown in Figures 5 to 8.

The feeding of matter on to the pressing surfaces will be determined to some extent by the nature of the particular matter being treated, but a localized stream of matter fed on to the central portion of a moving pressing surface is in most instances found to give the best results. In some instances where it is desired to use rolls of considerable width or axial length the pressing surface may be divided by suitable channels into a series of adjacent rings of pressing surface and the feed may be applied to the centre of each ring. Such an arrangement

may also be adopted, if desired, in the case of rigid bands or rings used in connection with such rolls.

For feeding a localized stream of matter 5 tubular members may be inserted in each division of the bite slightly in front of the region at which the material will be satisfactorily carried by the pressing surfaces and the tubular member may have a right- 10 angled spout pointing into the bite, preferably in the centre of the width of the pressing surfaces, the spout being carried into the bite until substantially in contact with the pressing surface upon each side.

15 The matter will be extruded from the spout by pressure in the tubular member and will issue as a cylinder or jet of the material to be pressed which almost immediately after issuing from the end of the 20 spout will contact upon each side with the pressing surface and be carried and spread thereby into a broad strip of material from which the more liquid constituents are extruded upon each side. If desired, a bracket 25 may project a small distance beyond the end of the spout in order to guide the jet of material until it is caught and supported by the pressing surfaces.

Presses in accordance with this invention 30 may be worked at any desired temperature and means for heating the interior of rolls or rigid and hollow bands may be provided. The heating employed may be of any desired nature, such as hot gases, live steam or recompressed vapour generated from previously 35 treated matter, the thin and uniform films of matter produced by apparatus in accordance with the invention being particularly applicable to further drying by 40 means of the small temperature differences which may be economically obtained when utilizing recompressed vapours.

The speeds of the moving pressing surfaces and the pressure exerted between them 45 will be graduated in accordance with the material to be treated and the complete treatment of any particular type of matter may be split up into two or more stages in which the speeds and pressures are adapt- 50 ed to the condition of the material in its varying states.

In many instances, where matter of large liquid content is under consideration, the 55 presses may be used in combination with draining, settling or filtering devices by means of which a portion of the liquid constituents may be separated from the matter which may then be more easily treated in presses in accordance with this invention.

60 In presses provided with rings and bands these may in some instances be formed of different materials which cooperate together to give a better result for certain purposes as, for example, plain steel bands may be 65 employed where heavy pressure is necessary

or steel bands alternating with softer material as, for example, rubber or the like, or two coating soft bands may be employed for matter which could be satisfactorily treated by means of lighter pressures.

70 Presses in accordance with this invention may be employed for obtaining oils, fats and the like from suitable sources, such as seeds, beans, nuts and other organic products and in such cases provision for heating the rolls and/or bands is preferably provided for obtaining the best results.

75 When treating matter from which a considerable amount of liquid is to be eliminated it is possible in accordance with this invention to so far reduce the liquid content that the matter may be conveniently broken up to an extent which enables it to be carried in a heated gaseous medium and drying of the solid constituents of the matter may, therefore, be completed in the waste flue gases of boilers which may supply power for the presses or any hot gaseous medium obtained from other sources.

80 Where so desired the whole of the press- 90 ing apparatus may be surrounded by a casing and heat may be introduced and any required temperature maintained therein, either in the atmosphere of the casing or through condensing steam in the interior of 95 the two drums or in any other suitable manner.

85 By operating as hereinbefore described it is possible to obtain a very large output 100 from apparatus of comparatively moderate dimensions and as only the two rolls require to be mounted in adjustable bearings and provided with devices for exerting the necessary pressure the apparatus will be of 105 very much lower cost in relation to the amount of product obtained. Further, as the operative portions of the apparatus are all collected within a small area the amount of labour and supervision for operating 110 such apparatus is very greatly reduced and at the same time the effect obtained is in every way equivalent to what could be otherwise obtained only by the use of pressing rolls of such large diameters that it 115 would not be possible to employ them in practice.

120 Apparatus in accordance with the invention may be employed either for the collection of the drier or wetter constituents of the matter or for both purposes simultaneously and such presses are particularly suitable for separating out liquids from materials such as peat, moss litter, lignite, sewage, spent hops, brewers' grain, oil seeds, 125 vegetable extracts, sugar cane, beet chips, wood pulp, sawdust and, generally, all materials which can be filtered or from which moisture can be squeezed or extruded.

130 It is to be understood that the apparatus hereinbefore described is given by way of

example only and that modifications and additions may be introduced without in any way departing from the spirit of this invention.

5 Claims:

1. Apparatus for removing liquid from material containing it comprising in combination pressing rolls with their axes substantially parallel with one another and 10 their circumferential surfaces closely adjacent, not less than one endless flexible band passing between said surfaces to divide into substantially equal compartments the more or less wedge-shaped cavity preceding the 15 bite of the rolls, means for feeding to each compartment the material to be treated and means pressing the axes of said rolls towards one another.

2. Apparatus for removing liquid from 20 material containing it, comprising in combination pressing rolls with their axes substantially parallel with one another and their circumferential surfaces closely adjacent, endless flexible bands surrounding 25 said rolls and passing between said surfaces to divide into substantially equal compartments the more or less wedge-shaped cavity preceding the bite of the rolls, means for feeding to substantially the centre of the 30 width of the bands in each compartment the material to be treated and means pressing the axes of said rolls towards one another.

3. Apparatus for removing liquid from 35 material containing it comprising in com-

bination pressing rolls with their axes substantially parallel with one another and their circumferential surfaces closely adjacent, not less than one endless flexible band passing between said surfaces to divide into 40 substantially equal compartments the more or less wedge-shaped cavity preceding the bite of the rolls, means for feeding to each compartment the material to be treated, means pressing the axes of said rolls 45 towards one another, and means for applying heat to the pressed material.

4. Apparatus for removing liquid from material containing it comprising in combination pressing rolls with their axes substantially parallel with one another and their circumferential surfaces closely adjacent, not less than one endless flexible band passing between said surfaces to divide into 50 substantially equal compartments the more or less wedge-shaped cavity preceding the bite of the rolls, means for feeding to each compartment the material to be treated, means pressing the axes of said rolls 55 towards one another, means for removing the 60 pressed material from the surfaces to which it adheres and means for delivering the said material into a moving current of hot gaseous medium.

In testimony whereof we have signed our 65 names to this specification.

OLOF SÖDERLUND.
TEORON BOBERG.
NILS TESTRUP.
